UNITED STATES PATENT OFFICE.

DANIEL CONNELLY, OF CLEVELAND HEIGHTS, AND CHRISTIAN E. SCHAFER, OF CLEVELAND,
OHIO.

STREET-FLUSHING APPARATUS.

No. 882,626.

Specification of Letters Patent. Patented March 24, 1908.

Application filed June 10, 1905. Serial No. 264,569.

To all whom it may concern:

Be it known that we, DANIEL CONNELLY, a citizen of the United States, residing at Cleveland Heights, in the county of Cuyahoga and State of Ohio, and CHRISTIAN E. SCHAFER, a citizen of the United States, residing at Cleveland, in the county of Cuyahoga and State of Ohio, have invented a certain new and useful Improvement in Street-
10 Flushing Apparatus, of which the following is a full, clear, and exact description, reference being had to the accompanying drawings.

Flushing wagons are mainly employed for
15 washing city pavements. They include a water tank and a tank of compressed air by means of which the water is discharged with greater or less force through nozzles which direct the streams of water against the pavements at the proper angle.

The object of this invention is to provide a flushing wagon of moderate cost which will be properly balanced on the trucks whether full or empty and which can be conveniently
25 put into condition for use and used under the various conditions existing at different places.

In the drawing, Figure 1 is a side elevation of a flushing wagon, embodying the invention. Fig. 2 is a rear end view thereof. Fig. 3 is a central vertical section through one of the valves containing vertical pipes to the lower end of which discharge nozzles are secured. Fig. 4 is a central vertical section through the valve mechanism by which connection can be established between the water tank and air tank.

Referring to the parts by letters A represents a cylindrical air tight water tank, preferably made of sheet metal. This water tank is firmly secured by means of straps *a* on the skeleton wagon body B. The water discharge pipe C, which is connected with the bottom of this tank near its middle, is also connected with the transverse pipe D. The vertical pipes E are connected with the ends of the pipe D, and the discharge nozzles e are connected with the ends of said pipes E.

K represents the compressed air tank which is located axially within the water tank and extends out through both ends thereof. This tank may be completed and made thoroughly air tight before being secured within the water tank; and, because of its location, the distribution of weight upon the wagon

wheels and springs is substantially the same 55 at all times whether the water tank be full or empty. In flushing wagons, as heretofore constructed, the compressed air tank has been formed within the water tank at one end thereof by an internal partition. It is difficult and somewhat expensive to make the joints between this partition and the walls of the tank air tight. Then again when such a tank is filled a greater proportion of the weight is borne by the rear wheels (provided 60 the air tank is at the front end of the water tank) than is the case when the tank is nearly empty of water.

M represents the pipe through which the water tank is filled. It is connected with the 70 bottom of the water tank at a point near the rear end thereof. A flexible hose through which connection is made between this pipe and the hydrant may be screwed upon the rear end of said pipe. When not in use this 75 flexible hose may hang over the projecting end of the air tank, being prevented from slipping off of the same by the flange k along the upper edge of the rear end of said air tank. A pipe N connected to the top of the 80 extended rear end of the air tank is likewise connected with the water tank, and it contains at n a reducing valve of any approved construction, so that whatever may be the air pressure within the tank K one may have 85 any other desired pressure less than that in the air tank within the water tank. There is another connection provided between the air and water tanks; a pipe P connected with the top of the air tank extends upward and 90 out through the top of the water tank. Valve mechanism is provided for this pipe by means of which communication between the two tanks may be prevented or permitted, as required. The valve mechanism shown is 95 constructed as follows:

A valve casing T is screwed onto pipe P, and it contains a valve *t* which will normally be closed by the air pressure within the air tank, and by a spring *t'*. Over this valve is 100 a hood S which screws into a flanged plate secured to the water tank and having holes therein. In the top of this hood is a stuffing box through which a valve operating rod *t* slides, said rod having a horizontal slot *t* in 105 its upper end. An eccentric V is pivoted to the top of the stuffing box, and lies in said slot *t*, and has an operating handle *v*. To

establish free communication between the two tanks, one turns this cam so as to push said rod t^2 downward. The air may then flow freely past valve t and through holes t^4 in the valve casing into the hood and thence into the water tank.

A valve casing R containing an ordinary check valve r is secured to the water tank over a hole therein. The valve opens inward, but has a light spring r' around its stem tending to close it. When the wagon is in service the air pressure in the tank holds it firmly closed. A dust hood X is secured over the valve casing—the purpose being to prevent the dust of the street from settling on the valve seat. One way of getting the wagon ready for service is to first fill the water tank with water, which compresses the air and forces it into the air tank past valve t , which will close automatically to prevent the air from flowing from the air tank into the water tank; then open the nozzle valves and allow the water to flow from tank A. While the water is so flowing out, the valve r will open automatically to allow air to get into tank A. Finally, the water tank is again filled with water, thereby compressing more air into tank K. When the reducing valve at n has been properly adjusted the wagon is ready for service. Another way to get it ready is to close all valves leading from the air tank, and force compressed air into said tank,—the pipe w connected with the projecting front end of said tank being provided for that purpose.

The vertical pipes E are constructed to serve as valve casing, and each of said pipes contains two valves. One valve H is moved downward to its seat by a spring h , and is held down additionally by the pressure of water from tank A. Its stem h' extends out through the top of said pipe, whereby it may be operated by a lever I near the seat,—through suitable transmitting mechanism, as for example the bell crank lever J and the two links j, j' . The other valve F is moved upward to its seat by a spring f , and away from its seat by the pressure in the tank. The purpose of this valve is to prevent apparatus from working inefficiently and to prevent the escape of air in case the driver allows all of the water to run out before he closes valve H. Under ordinary conditions the reducing valve at n is set so that the pressure in tank A will be about ten pounds. In that event the spring f will be set for about eight pounds. If, therefore, the pressure in the tank ever gets below eight pounds this valve will close automatically and prevent the escape of the water, or air, even though valve H remains open. Since the efficiency of flushing wagons is dependent upon the forceful expulsion of the water from the nozzles, it is evident that this valve is a valuable feature of construction in flushing

wagons which are operated by men whose intelligence is not always of a very high order.

Having described our invention, we claim:

1. In a flushing wagon, the combination of a water tank secured upon the wagon body and having a valve controlled discharge pipe, an air tank extending horizontally through the water tank and out through both ends thereof, and a valve-controlled connection between said tanks.

2. In a flushing wagon, the combination of a horizontal water tank secured upon the wagon body, and having a valve controlled discharge pipe, an air tank which extends horizontally through the water tank and out through one end thereof, a pipe connected with the projecting end of said air tank and with the water tank, and a reducing valve in said pipe.

3. In a flushing wagon, the combination of a water tank secured upon the wagon body and having valve controlled discharge pipe, an air tank extending horizontally through the water tank from end to end, and projecting through the rear end of said tank, and a flange secured along the upper edge of the projecting rear end of said air tank,—said water tank having, near its rear end, a valve controlled feed pipe to which a flexible pipe may be connected.

4. In a flushing wagon, the combination of a horizontal water tank secured upon the wagon body, an air tank in the water tank, a valved pipe connected with the air tank and extending out through the water tank, a hood secured to the water tank over said pipe, a valve operating rod extending through the wall of said hood, and mechanism mounted upon the outside of said hood for operating said rod.

5. In a flushing wagon, the combination of a water tank, an air tank contained therein, a pipe connecting said tanks, a discharge pipe connected with the water tank having a discharge nozzle connected with said pipe, a valve in said pipe, mechanism operable from the driver's seat for moving said valve, a second valve in said discharge pipe and a spring for closing the same against the pressure in the tank.

6. In a flushing wagon, the combination of a water tank, an air tank, a pipe connecting said tanks, and a discharge pipe connected with the water tank, with a valve in said discharge pipe, mechanism for operating said valve, and a self closing valve in said discharge pipe provided with a spring operating to close the same against the pressure in the tank.

7. In a flushing wagon, the combination of a water tank, an air tank, a pipe connecting said tanks, and a discharge pipe connected with the water tank, with a valve in said discharge pipe and movable outward toward its

seat, whereby the pressure in the tanks tends to hold the valve closed, mechanism for opening said valve, and a second valve in said discharge pipe which is movable inward against its seat, whereby the pressure from the tank tends to open said valve, and a spring operating to close the same, substantially as specified.

In testimony whereof, we hereunto affix our signatures in the presence of two witnesses.
